UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,144,419.

Specification of Letters Patent. Patented June 29, 1915.

Application filed February 28, 1914. Serial No. 821,801.

To all whom it may concern:

Be it known that I, CHARLES J. KLEIN, a citizen of the United States, residing at Milwaukee, in the county of Milwaukee and 5 State of Wisconsin, have invented new and useful Improvements in Electric Switches, of which the following is a full, clear, concise, and exact description, reference being had to the accompanying drawing, forming 10 a part of this specification.

This invention relates to electric switches and with respect to its more specific features, to improved snap switches adapted to make and to break circuit with a quick 15 action.

Various objects and advantages of the invention will appear hereinafter in connection with the description of a preferred embodiment of my improved device illustrated in the accompanying drawing, 20 wherein,

Figure 1 is a perspective enlarged view of parts of a switch mechanism; Fig. 2 is 25 a top view of the mechanism incorporated in a surface switch device, the operating member being removed; Fig. 3 is a sectional view on the line 3—3 of Fig. 2, with the operating member in position; Fig. 4 is a sectional view on the line 4—4 of Fig. 2; and, 30 Fig. 5 is a sectional detail view on the line 5—5 of Fig. 2.

The switch mechanism illustrated comprises, in general, a reciprocating operating member 1, an oscillating contact member 2, 35 and an energy storing operative connection between the same including resilient means 3 carried by the operating member.

Referring more specifically to the drawing, the switch operating member comprises 40 a stamped metal plate 4 provided on its opposite ends with push-buttons 5 of insulating material. The contact member also preferably comprises stamped sheets 6 coincidentally superposed and having opposite radial extensions 7 constituting contact fingers adapted to engage stationary contacts. This contact member is centrally pivoted on a base by suitable means, such as a shouldered screw 8. The operating 45 member is designed to reciprocate above the contact and is supported by two angle frames 9 having apertures through which the push buttons 5 project. These frames may be rigidly secured to the base, which 50 supports the contact, by screws 10.

The connection provided between the operating and contact members is such that the resilient means acts alternately during each reciprocation of the operating member to impede and impel movement of the contact. This resilient means is in the form of a forked spring 3 having transversely aligned prongs 11 and 12 biased apart and reciprocable with the operating member. The extremities of these prongs bear 60 against cams 13 and 14 respectively provided on opposite sides of the pivotal axis of the contact. The cam 13 is convex, the cam 14 is concave, and both are preferably formed by providing suitable apertures in 70 the contact member (Fig. 1). In practice, the inclination of the convex cams 13 to the longitudinal axis of the operating member is slightly greater than the inclination of the opposite concave cams (Fig. 2) so that 75 the action of the spring prong 11 dominates the action of the prong 12 as the operating member is reciprocated.

The relation of the parts described is such that movement of the operating member 80 carries the spring 3 therewith so that the prongs of the latter ride over the cams and are tensioned until the prong 11 passes the apex of the convex cam whereupon tension of the spring is released and the contact member is oscillated to its opposite extreme position with a quick and positive snap movement.

Referring to Figs. 2 to 5, the switch mechanism illustrated is incorporated in a surface receptacle. In this embodiment a rectangular insulating base 15 is provided with a central recess 16 in which the current carrying parts of the switch are arranged. 90

The contact member is pivotally mounted 95 in the base recess and is disposed to oscillate between a pair of stationary switch contacts 17 mounted at opposite ends of the base and having binding posts 18 for connection with line terminals entering the casing through 100 adjacent apertures 19. The operating member is mounted to reciprocate across the base, the end walls of which are suitably cut-away to accommodate the push-buttons 5. Fig. 5 shows a preferred manner of mounting the 105 stationary contacts 17 on the insulating base. As there shown, each contact has a lateral finger 20 beveled at its extremity and adapted to wedge between the bridging fingers 7 of the moving contacts. 110

The operation of the mechanism is as follows: Assuming the switch to be in "on" position (Fig. 2) pressure on the right push-button moves the spring 3 toward the left. 5 The spring prong 11 thereupon rides over the right half of the convex cam 13 and is accordingly pressed inwardly and tensioned. It is to be noted that during such movement this prong is acting on the contact to hold 10 the same in "on" position. The opposite spring prong 12 simultaneously rides over the left half of the concave cam and tends to move the contact to "off" position. As above described, however, the cam inclinations are unequal and the spring prong 11 15 dominates the other so that the contact is not moved until reciprocation of the operating member carries the prong 11 past the crest of the convex cam. Thereupon the energy stored in both forks of the spring cause 20 to oscillate the contact member to its opposite extreme position with a snap movement, thereby interrupting the circuit between the stationary switch contacts. Reverse movement 25 of the operating member effects a snap reversal of the contact member in a manner similar to that described. Reciprocation of the operating member is limited by any suitable means; for example, shoulders 21 on 30 the push-buttons which abut the walls of the supporting frames 9. Moreover, movement of the operating member is limited at substantially the moment the contact member is actuated so that strain on the parts is 35 minimized. No separate means is required for limiting the oscillation of the contact member since the spring prongs 11 and 12 respectively rest in an extremity of the convex aperture 13 and in the valley of the concave aperture 14 and act to prevent an overthrow of the contact in either direction. In 40 practice the shanks of the push-buttons 5 and the apertures in the frame 9 receiving the same are preferably rectangular so that 45 displacement of the spring 3 is insured against. By providing the spring 3 with two opposed forks, as described, lateral strain on the operating member is substantially equalized and the contact actuating 50 force increased. Furthermore, by arranging the spring to exert force in directions at right angles to the pivotal axis of the contact, the latter may be loosely journaled and will move with little frictional resistance. 55 What I claim as new and desire to secure by Letters Patent is:

1. In an electric switch, in combination, an oscillating contact member having a convex cam and a concave cam on opposite sides 60 of its pivotal axis, and a reciprocating operating member having resilient means acting on said cams in opposite directions to alternately impede and impel oscillation of said contact member during each reciprocation of said operating member.

2. In an electric switch, in combination, an oscillating contact member having a convex cam on one side of its axis, a reciprocating operating member movable across said contact member, and a looped spring carried by said operating member and having its free extremity biased against said cam and movable thereover to alternately impede and impel oscillation of said contact member during each reciprocation of said operating member. 70

3. In an electric switch, in combination, a reciprocating member, an oscillating member, one of said members being an operating member and the other a contact member, 80 and a spring carried by said operating member and having extremities biased apart and constantly engaging said contact member on opposite sides of the pivotal axis of the oscillating member to alternately impede and 85 impel movement of the contact member during each actuation of the operating member.

4. In an electric switch, in combination, a reciprocating member, an oscillating member, one of the same being an operating 90 member and the other a contact member, a spring carried by said reciprocating member and having forked extremities in constant engagement with said oscillating member on opposite sides of the pivotal axis 95 thereof to alternately impede and impel movement of the contact member during each actuation of the operating member.

5. In an electric switch, in combination, a reciprocating operating member having opposed push-button extremities, an oscillating contact member and a spring carried by said operating member and having extremities biased apart and constantly engaging said contact member on opposite 100 sides of the pivotal axis thereof.

6. In an electric switch, in combination, a reciprocating member, an oscillating member having a convex cam and a concave cam on opposite sides of its pivotal axis, one of said members being an operating member and the other a contact member, a forked spring carried by said reciprocating member having extremities restrained by said cams and riding over the same during each 110 actuation of the operating member to resist movement of the contact member during a predetermined initial movement of the operating member and thereafter to actuate the contact member with a snap movement. 115

7. In an electric switch, in combination, a reciprocating operating member, an oscillating contact member having a convex cam and a concave cam on opposite sides of its pivotal axis, resilient means carried by said 125 operating member and acting on said convex cam to move the contact member in opposite directions during each reciprocation of the operating member, and resilient means also carried by the operating member and acting 130

on said concave cam to move said contact member in a single direction during each reciprocation of the operating member, said first mentioned means opposing and dominating said second mentioned means.

8. In an electric switch, in combination, a reciprocating operating member, an oscillating contact member having a convex and a concave cam on opposite sides of its pivotal axis, resilient means carried by said operating member and acting on said convex cam to move the contact member in opposite directions during each reciprocation of the operating member, and resilient means also carried by the operating member and acting on said concave cam to move said contact member in a single direction during each reciprocation of the operating member, said first mentioned means opposing and dominating said second mentioned means during partial reciprocation of the operating member and cooperating with said second-mentioned means thereafter.

9. In an electric switch, in combination, a reciprocating operating member, an oscillating contact member having a convex and a concave cam on opposite sides of its pivotal axis, the inclination of said convex cam to the longitudinal axis of the operating mem-

ber being greater than the inclination of the opposed face of said concave cam, and a forked spring carried by said operating member and having its extremities laterally acting on said cams in opposed directions during predetermined initial movement of said operating member and in the same direction thereafter.

10. In an electric switch device, in combination, a supporting base, a pivotally mounted contact member thereon having opposed convex and concave cams on opposite sides of its pivotal axis, a reciprocating operating member movable across said contact member, and a forked spring carried by said operating member having its extremities biased apart and acting on said cams to effect a snap movement of said contact member as said operating member approaches its limit of reciprocation in either direction.

In witness whereof, I have hereunto subscribed my name in the presence of two witnesses.

CHARLES J. KLEIN.
